Patented Apr. 19, 1966

204,536

WATER SPRINKLER BASE

Curtis Maddox, 4209 W. Nichols Ave., Sacramento, Calif.,
and Theodore N. Tripp, 7240 Filbert Ave., Orangevale,
Calif.

Filed June 2, 1965, Ser. No. 85,545

Term of patent 14 years

(Cl. D91—3)

FIG. 1

FIG. 2

FIG. 3

FIG. 4

FIG. 5

FIGURE 1 is a perspective view of a water sprinkler base, showing our new design;

FIGURE 2 is a top plan view thereof;

FIGURE 3 is a bottom plan view;

FIGURE 4 is a front elevational view of FIGURE 1; and,

FIGURE 5 is a horizontal sectional view, the plane of the section being indicated by the line 5—5 in FIGURE 4.

We claim:

The ornamental design for a water sprinkler base, as shown.
